UNITED STATES PATENT OFFICE

ANDREW EPPLER, OF LYNN, MASSACHUSETTS, ASSIGNOR TO UNITED SHOE MACHINERY CORPORATION, OF PATERSON, NEW JERSEY, A CORPORATION OF NEW JERSEY

SHOE SEWING MACHINE

Application filed April 11, 1929, Serial No. 354,201. Renewed July 15, 1932.

The present invention has relation to sewing machines and more especially to inseam welt shoe sewing machines of the type provided with a curved hook needle, adapted to form a chain stitch, and employed to sew the inseams of shoes.

The invention refers particularly to machines of the said type which are designed to lay the chain in the channel of the insole, through entering the needle into the work from the channel side thereof. The placing of the chain in the channel has practical advantages over the more common practice of putting the chain upon the welt, as the doubled thread of the chain is less apt to cut the insole when made of soft material, and the single thread on the welt permits the outseam to be brought in close to the upper without danger of cutting the inseams in the stitching, and at the same time allows the inseam to be put more nearly under the exact edge of the insole. The inseam thus made can be trimmed more closely, so that the insole and outsole come closer together and less filler need be used between them. Also, the needle enters the channel and can more easily be made to strike it accurately without tearing up the insole.

It is the preferred practice to control the formation of the stitches of an inseam having its chain laid upon the welt by the use of stitch forming devices comprising a take-up and a thread finger, the take-up being timed to draw a loop of thread tight around the shank of the needle while the needle is in the work and the thread finger being timed to measure off thread between the looper and the work while the needle is through the work in order to provide thread for the work side of the next loop during the retracting stroke of the needle. For the reasons hereinafter stated, however, this practice has not been followed in controlling the formation of the stitches of an inseam having its chain laid in the channel although it is well recognized that an inseam formed by stitch forming devices comprising a take-up and a thread finger is tighter, more uniform and more satisfactory than when the stitches are formed and tightened in any other manner.

When the chain is laid upon the welt, the needle pulls a loop of thread from the channel through the between substance and out from the welt, drawing the work side of its loop snugly into the bottom of the channel and pulling upon the thread against the resistance offered by the tension to tighten the stitch at this stage in its formation. Then the needle again enters the work, and the take-up pulls upon the supply end in the opposite direction from the needle-pull, drawing the loop tight about the shank of the needle and pulling the thread against the tension resistance to exert a stitch setting strain on the seam. The channel side of the between substance is always at a fixed distance from the needle-hook when the needle is in the farthest retracted position, because the bottom of the channel is held against the channel guide, and the channel guide is always at a fixed distance from the needle when the latter reaches its point of greatest retraction. Hence, with stitches of equal length, the same amount of thread is drawn by the needle to tighten the stitch regardless of variations in the thickness of the between substance and a take-up and a thread finger having a uniform and unvarying action in giving up thread to the needle can be used without causing reeing in the hook of the needle with consequent injury to and possible breakage of the thread.

When the chain is laid in the channel, however, the conditions are quite different. To lay the chain in the channel, it is necessary to enter the needle into the work from the channel side thereof. Then when the needle is retracted, it draws out from the channel a loop of thread, and pulls the work side of such loop tight against the welt. This welt-surface of the work varies in distance from the channel guide in direct proportion to the variations in thickness of the between substance. Hence this welt-surface also varies in distance from the needle when the latter is at its farthest retracted position, in direct proportion to the thickness of the between substance. Consequently, to permit the needle to retract and tighten the stitch without causing the thread to reeve in the

hook of the needle, it is necessary to provide the needle, during its retracting stroke, with more or less thread as the thickness of the between substance varies at various 5 points in the circuit of the shoe. A take-up and thread finger arranged to operate as in a machine which lays the chain on the welt will not accomplish this result since they always deliver to the needle the same amount 10 of thread for all thicknesses of stock, as has been explained in the description of the operation of such a machine given above, and for this reason other means have been relied upon in previous attempts to improve the 15 operation of machines laying the chain in the channel.

Having in mind the state of the art as above outlined, the object of the present invention is to provide a novel and improved inseam 20 shoe sewing machine laying the chain in the channel and insuring a tight seam by pulling the thread tight each time it is laid along either the welt or the channel side of the between substance without objectionable and 25 preferably no reeving of the thread through the needle-hook.

To this end, the invention contemplates the provision in a chain stitch inseam shoe sewing machine having its curved hook needle 30 arranged to enter the work from the channel side, of a take-up and a thread finger acting, respectively, to draw tight the loop of thread around the shank of the needle while the needle is in the work, and to measure off 35 thread between the looper and the work, constructed and arranged to give up to the needle during its retracting stroke an amount of thread varying with the thickness of the work. In its broader aspects, the invention 40 contemplates the provision of any suitable construction, combination and arrangement of parts which enables the take-up and thread finger to operate in this manner. In the embodiment of the invention hereinafter specifically described, the desired result is 45 secured by utilizing the thread finger to draw from the supply more or less thread as the work varies in thickness. To avoid the necessity of additional parts, or complications in 50 the construction and arrangement of mechanism for actuating the thread finger, the desired action of the thread finger in pulling off thread is secured by arranging the thread finger to move in such a path that the increase and decrease in the thickness of the work will automatically cause the thread arm 55 to draw from the supply the proper amount of thread to compensate for the varying thickness of the work. Preferably the thread finger 60 is so arranged and actuated that it cooperates with the work itself in drawing thread from the supply, the thread finger being arranged to engage the thread between the looper and the adjacent surface of the 65 work and being movable in a path to cause

said surface to cooperate, through its relative shift in position due to variations in the thickness of the work, with the thread finger to draw a varying amount of thread from the supply. The path of the thread finger can be so arranged that any desired amount of thread may be drawn from the supply. In the sewing of a shoe, the variation in the thickness of the materials through which the inseam passes is due principally to the increased thickness at the toe portion of the shoe, and it has been found in actual practice that while the material increases in thickness at the toe portion of the shoe, it is not of a solid nature at this point, being more or less pleated and having a tendency to pull away from the shoulder of the insole. Consequently, during the sewing of the seam, this material is compressed and drawn tightly against the shoulder of the insole and for this reason, and also on account of the tendency of the thread to stretch slightly, the thread finger is arranged to draw from the supply an extra amount of thread less than twice the increase in the thickness of the material, which amount apparently would be required to enable the needle to properly tighten the stitch if the compressibility of the material and the stretch of the thread were not taken into account. To secure the best results both as to tightness of seam and freedom from reeving of the thread in the hook of the needle, the thread finger in the preferred form of the invention, is arranged to move in such a path as to cause a length of thread to be drawn from the supply which increases and decreases an amount substantially equal to increases and decreases in the thickness of the work.

In addition to the features of invention above referred to, the present invention also consists in the devices, combinations, and arrangements of parts hereinafter described and claimed.

While the invention is illustrated and described in connection with a machine for sewing welt shoes, it is to be understood that the principles of the invention are not to be limited in their application to such machines, but are equally applicable to turn shoe sewing machines, and in other connections within the scope of the claims appended hereto.

The invention will be readily understood from the accompanying drawings illustrating a machine embodying the invention in its preferred form, and the following detailed description of the construction therein shown.

In the drawings, Fig. 1 is a side elevation of a welt shoe sewing machine including the improvements of the invention, certain parts not essential to the invention being omitted; Fig. 2 is a view in vertical section on line 2-2 of Fig. 1, looking in the direction of the arrows and showing in profile the cam which

acts to release the needle tension; Figs. 3 to 7 illustrate diagrammatically in sequence the various steps in the cycle of making a stitch in the improved manner of the invention; 5 Fig. 8 shows on a larger scale, and in similar manner to Figs. 3 to 7, the manner in which the increase in thickness of the between substance increases the length of thread provided for the stitch.

10 Having reference to the drawings, the invention is shown embodied in an Eppler type welter such as is shown and described in U. S. Patent No. 950,616, granted to the present inventor on March 1, 1910, for Shoe 15 sewing machine. The present machine is organized to lay the chain in the channel, as in the patent, and in respect to the needle 1, the needle guide 2, the back gage 3, the welt guide 4, the looper 5, and the awl 6, and their actuating cams upon the cam disks 7, 8, and 9, the arrangement and operation are the same as in said patent, to which reference may be had for a full and complete description of these parts.

20 25 In accordance with the invention, there is combined with the said parts a thread measuring finger 10 having a forked extremity to engage the thread between the looper and its point of emergence from the last-formed 30 needle-hole in the work. This thread finger is secured in a carrier 11 pivotally mounted upon a cap-screw 12 fixed in the frame of the machine, its attachment to said carrier being effected by screws 13 whose shanks pass 35 through oversized holes in the carrier 11, permitting adjustment of the thread-engaging end of the thread-finger to vary the effective radius on which the thread finger is swung and its distance from the surface of 40 the work and consequently to vary the amplitude of its throw, the relation of its path to the work, and its resulting measuring or thread drawing effect. The thread finger moves back and forth in a plane at right angles to the direction of feed of the work, its 45 end engaging with the thread between the looper and the work and diverting it from its straight line and producing a bend or loop by its upward and forward movement. The 50 surface of the welt at one end of the needle hole last formed acts as one abutment in measuring off this bend or loop, while the lower end of the looper 5 acts as the other abutment.

55 60 65 To actuate the thread finger, its carrier 11 is pivotally connected at 14 with a link 15 pivoted at 16 to the end of a cam lever 17 fulcrumed at 18 upon the machine frame and provided at its upper end with a cam roll 18 upon a stud 19, the said cam roll engaging with a cam 20 shown in dotted lines, formed upon one end of the cam disk 9. This means of actuation imparts the aforesaid swinging movement of the thread finger at right angles 65 to the direction of the feed of the work.

To facilitate the action of the thread finger in drawing aside a bend or loop of thread, it is desirable to relieve materially the tension upon the thread while such thread finger is acting. This is effected by utilizing the tension releasing device shown and described in the aforesaid U. S. Patent No. 950,616, and forming the subject-matter of U. S. Patent No. 1,011,177, also granted to the present inventor, on December 12, 1911, for Tension releasing device. This mechanism as disclosed in said patents, releases the tension on stopping the machine and comprises a toggle linkage 21, 22 for releasing the tension truck 23 from the braking pressure of its spring which linkage is actuated through the rotation of a sleeve 24 upon a shaft mounted fixedly in the framework of the machine. The sleeve 24 is actuated by an arm 25 secured to said sleeve and carrying upon its upper end a segment 26 which is loosely pivoted to said arm. This segment has two segmental surfaces both concentric with the pivot joining the segment to the arm 25, but of unequal radii, and said surfaces are held by a spring 27 in contact with a circular disk 28 fixed concentrically upon the main shaft 29 of the machine. Between the two segmental surfaces there is applied to the segments a tooth which upon reverse rotation of the shaft 29 after the stitching has been finished, is brought into engagement with a gear 30 upon said shaft closely adjacent to the circular disk 28, the function of said tooth in its engagement with the gear 30 being to bring the segmental surface having the longer radius into contact with the circular disk 28 to move and retain the arm 25 laterally away from the main shaft and straighten the toggle link 21, 22.

To utilize this mechanism just described to effect the periodic release of the tension at the point in each stitch-forming cycle when the thread finger 10 is acting to measure the thread for the next succeeding stitch, a cam 31 having the form shown in profile in Fig. 2, is fixed upon the shaft 29 close beside the gear 30. Upon the pivot 32 connecting said segment 26 with the arm 25 is pivotally mounted an arm 33 which has a cam roll 34 upon a stud 35 fixed in said arm 33 intermediate its length. This cam roll is caused to follow the periphery of cam 31 by the action of the spring 27 previously referred to. The other end of the arm 33 is provided with an eye 36 through which is passed the shaft 29 in assembling the machine in order to support the arm in horizontal relation, the elongated shape of said eye permitting the necessary lateral movement of arms 33 and 25 effected by the cam 31 as it engages the cam roll 34 in the course of its rotation. The movement of the arm 25 effects the momentary release of the tension truck 23 from engagement with its co-acting braking surface, and allows the

thread finger 10 to draw thread from the wax pot without having to overcome any friction other than that incidental to drawing the thread through the stripper and around the trucks over which it passes as led to the needle.

A second tension-imposing device is combined with the means just described for creating and releasing the needle-tension, in order to assist the take-up 37 in drawing tightly against the channel side of the work a loop of thread surrounding the shank of the needle as the needle re-enters the work. This take-up tension mechanism comprising a brake shoe 38 adapted to be pressed against the periphery of a cylindrical portion 39 of the thread truck 23, its shank 40 being borne within a sleeve 41 upon one end of a bell crank lever 42, and it is pressed yieldingly against the periphery of said portion by means of an expanding spiral spring 43 surrounding its shank and confined between lock nuts 44 applied to said shank and the proximate end of the sleeve 41. A collar 45 is affixed to the protruding opposite end of the shank 40 by means of a clamping screw, to limit the movement of the shank within the sleeve 41 under the influence of spring 43, so that the brake shoe 38 may be lifted out of contact with the cylindrical portion 39 of the tension truck 23 by the movement of the bell crank 42. The bell crank 42 is pivotally mounted at 46 upon the frame of the machine and has its opposite extremity pivotally connected at 47 with a link which is joined at 48 with a cam lever 49 pivoted upon the machine frame at 50 and having at 51 a cam roll engaging with a disk cam 52 upon the shaft 29, said cam roll being pressed against the side of such cam by the action of a spring 53 coiled about the pivot 46 of the bell crank 42, having one of its ends engaged with the machine frame and the other with one arm of the bell crank 42. Means for adjusting the relation of the parts to vary the force and duration of the braking effect resulting from the engagement of the brake shoe 38 with its co-acting cylindrical surface 39 comprise devices for extending or shortening the length of the link between the bell crank and the cam lever 49, namely, the formation of the said link with a turn-buckle 54 uniting the oppositely-threaded rods 55, 56, and provided with lock nuts 57 for securing the link in adjusted relation.

The take-up 37 comprises a thread truck rotating freely upon a cap screw 58 fixed in the end of an arm 59 upon a sleeve 60 which is rotatably mounted upon a stud 61 on the machine frame. At the other end of such sleeve 60 is formed a short arm 62, to the extremity of which is connected at 63 a link 64 joined pivotally at 65 to the lower end of a cam lever 66 which is pivoted at 67 upon the machine frame and receives actuation from

the cam disc 9 through engagement of such cam disc with a cam roll mounted upon a stud 69 at the upper end of said cam lever.

To cause the cam rolls located respectively at the upper ends of the take-up cam lever 66 and the thread finger cam lever 17 to follow their co-acting cams upon the cam disc 9, each of said levers is provided near its upper extremity with a pin 68 fixed therein and to these pins are attached the opposite ends of a contracting spiral spring 70, acting to force said cam rolls yieldingly against their respective cam surfaces.

The novel method of operation of the organization described is illustrated diagrammatically in Figs. 3 to 7 inclusive. After the needle passes through the work and emerges from the welt side thereof, the thread finger 10 moves forward at right angles to the direction of feed of the work and engages the thread between the looper and the point where the thread emerges from the work at the last-formed needle hole therein. The thread finger thus pulls aside from the direct line between said looper and said needle hole a loop or bend of thread, which it retains while the looper is making its circuit of the needle and engaging the thread with the hook of said needle. During the thread finger's operation, both the needle tension and the take-up tension are released. The parts are now in the relation shown in Fig. 3, with the take-up 37 substantially half-way down in its thread-giving movement. Next the needle starts back through the work, the thread finger moving rearwardly out of engagement with the bend or loop which it has measured off for the needle, the looper moves aside, and the take-up descends a trifle farther to yield thread and prevent reeving of the thread through the hook of the needle with undesired shortening of the measured loop, all as shown in Fig. 4. As the needle recedes through the work, the needle tension is applied by means of the cam 31 and the parts controlling the tension truck 23 therefrom. The take-up continues its downward thread-delivering movement, but at a slightly slower rate than that at which the needle is drawing the supply end of its loop through the work, so that as the needle reaches its point of farthest retraction as shown in Fig. 5, the tension on the two legs of the loop drawn through is substantially equal, the increase in the tension of the supply side achieved as just described serving to balance the tension on the work side of such loop caused by drawing the thread tightly against the welt side of the work and compressing the between substance by the pull of the needle. In thus pulling one side of the stitch tight against the welt side of the work, there is no apparent reeving of the thread through the hook of the needle, owing to the balanced tension in both legs of the needle loop.

With the needle tension still on, the take-up tension is applied and the work is fed by the awl. As the needle approaches the channel and re-enters the work, the take-up 37 starts upwardly, pulling rearwardly on the supply end of the thread and shortening the needle loop drawn through the work as just described so that it stands about the shank of the needle after its re-entry into the work, as shown in Fig. 6. Continuance of the upward movement of the take-up 37 with the needle tension and the take-up tension both still applied, results in drawing the needle loop tightly about the shank of the needle and 15 against the channel surface of the work, as shown in Fig. 7, and theitch-forming cycle has been completed.

The manner in which the invention provides for automatically compensating for increased thickness of the between substance at 20 various points in the circuit of the shoe will be clearly understood from an inspection of Fig. 8. Therein is shown on a large scale the relation of the parts to the work after 25 the thread finger 10 has acted to measure off the bend or loop of thread for the next needle loop, and as the looper is looping the thread into the hook of the needle, but before the thread finger has released such bend 30 or loop. The length of thread entering into the work side of the next needle loop to be drawn through the work is equal to the stretch of thread which extends from the welt surface of the work at E, up over the thread 35 finger at B, and to the hook of the needle at C. When the needle is retracted, with the parts in proper adjustment, this length of thread will be just adequate to carry the needle back to its point of farthest retraction 40 without reeving through the hook of the needle, the tension on this length of thread as the needle draws it tight against the welt side of the work being balanced as aforesaid by the needle tension applied to the supply 45 side of the loop and the lagging of the giving-up action of the take-up 37. In the event that the work increases in thickness, as for example, to an extent such as would bring the surface of the welt to the point D, it will 50 be seen that the length of thread from the channel at A to the hook of the needle at C will have been increased by the length E—D, the thread entering into the making of the work-side of the next needle loop following 55 the path D—B—C. The length of the bend or loop E—B—C held aside by the thread finger differs in no substantial extent from the length D—B—C; hence the thread finger draws aside substantially the same length of 60 thread with thick stock as with thin. But, on thick stock, the needle hook, after engaging the thread, travels a less distance before entering the stock due to the fact that the welt surface is nearer the source of supply, and consequently more of the thread 65 given up by the thread finger and take-up, is available for the needle loop during the continued retracting movement of the needle. On thick stock, the needle hook as it is circled by the looper engages the thread farther 70 away from the channel than on thin, though the thread finger and looper have each a constant throw, that is, the length of thread between the needle hook and the channel is greater with thick stock than with thin stock, 75 and this increase in the length of thread between channel and needle hook is secured by using the looper as one abutment about which the thread is bent aside by the thread finger, and by using as the other abutment the surface of the welt, which varies its distance from the channel in direct proportion to the thickness of the stock. By the novel arrangement of the thread finger with respect 80 to the surface of the work, as indicated in the drawings, the thread finger is made to add to the work side of the needle-loop a length of thread equivalent to the work's increase in thickness at the exact point being stitched. There is an increase in the length of the 85 thread drawn into the system, as measured from the tension to the channel guide, as the work increases in thickness, even though the length of the loop or bend drawn aside by the thread finger between the surface of the 90 welt and the looper remains unchanged, and this increase in length results from the more devious path, A—D—B—C, of the thread between the channel and the looper with thick stock than that, A—E—B—C, followed 95 with thin stock. As stated hereinbefore, the uncompacted state of the between substance permits it to be compressed to such an extent by the work side of the needle loop when the latter is drawn tight by the needle as in Fig. 100 5, as to make this amount in practice a complete and accurate compensation which disposes of all observable reeving in the hook of the needle.

Since the variation in thickness of the work does not vary the position of the channel side of the work, the needle loop is always drawn out of the channel the same distance, and when the needle re-enters the work, the take-up, having a constant throw, retrieves the 110 same amount of thread from the work in drawing the needle loop tight around the shank of the needle and against the channel side of the work. The movement of the take-up continues after tightening this loop, and in completing its working stroke it draws from the supply a length of thread 115 entering into the formation of the next succeeding stitch, which length as drawn by the take-up is also always the same. The action of the thread finger, in its peculiar co-operation with the abutment formed by the surface of the welt, causes it to add to this length drawn by the take-up an amount 120 which it draws from the supply with both 125 65

tensions off, and to proportion this added amount to the thickness of the work at the point being stitched.

The nature and scope of the invention having been indicated and a mechanism embodying the invention having been specifically described, what is claimed is:

1. A hook needle, chain stitch inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper, and a thread finger movable transversely to the stretch of the thread from the looper to the work in a path to cause a length of thread to be drawn from the supply increasing and decreasing an amount substantially equal to increases and decreases in the thickness of the work.
2. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper, and a thread finger movable transversely to the stretch of the thread from the looper to the work in a path to cause a length of thread to be drawn from the supply varying with the thickness of the work.

3. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper, a thread finger engaging the thread between the work and the looper, a thread tension mechanism and means for controlling said mechanism to release the tension on the thread during the thread drawing movement of the thread finger.

4. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper, a thread finger engaging the thread between the work and the looper, a thread tension mechanism, means for controlling the thread tension mechanism to release the tension on the thread during the thread drawing movement of the thread finger, to apply a tension to the thread during the retraction of

the needle, and to apply a heavier tension to the thread during the pull of the take-up.

5. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper and a thread finger engaging the thread between the work and the looper arranged to co-operate with the work during its thread drawing movement to draw from the supply a length of thread varying with the thickness of the work.

6. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper, and a thread finger engaging the thread between the looper and the adjacent surface of the work and movable in a path to cause said surface to cooperate, through its relative shift in position due to variations in thickness of the work, with said thread finger to draw from the supply varying amounts of thread to compensate for such variations in thickness.

7. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work and thereafter pull a uniform amount of thread from the supply regardless of variations in the thickness of the work, a looper, and a thread finger movable transversely to the stretch of the thread from the looper to the work acting after the thread pulling movement of the take-up to pull from the supply an amount of thread varying with the thickness of the work.

8. A hook needle, chain stitch, inseam shoe sewing machine having, in combination, a needle arranged to enter the work from the channel side thereof, a take-up acting to draw tight a loop of thread around the shank of the needle while the needle is in the work and to draw thread from the supply, a looper, and a thread finger engaging the thread between the work and the looper, said take-up and thread finger cooperating to draw a length of thread from the supply varying with the thickness of the work an amount permitting the needle to tighten the stitch without reeving of the thread in the needle hook.

9. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work and to draw thread from the supply, a looper, and a thread finger engaging the thread between the work and the looper, said take-up and thread finger cooperating to draw from the supply a length of thread increasing and decreasing an amount substantially equal to 15 increases and decreases in the thickness of the work.

10. A hook needle, chain stitch, inseam shoe sewing machine having, in combination, a needle arranged to enter the work from the channel side thereof and during its retracting stroke to exert a stitch tightening strain on the thread, a take-up acting to draw tight a loop of thread around the shank of the needle while the needle is in the work, a looper, a thread finger engaging the thread between the work and the looper, and means for actuating the take-up and thread finger to give up to the needle during its retracting stroke and after the needle hook enters the work an amount of thread varying with the thickness of the work.

11. A hook needle, chain stitch, inseam shoe sewing machine having, in combination, a needle and a channel guide located on one side of the work, said needle acting during its retracting stroke to exert a stitch tightening strain on the thread, a take-up acting to pull tight a loop of thread about the shank of the needle while the latter is in the work, and 40 a looper and thread finger upon the opposite side of the work and coacting with the surface of the work to vary the length of thread between the channel and the hook of the needle at the completion of the looping operation, in proportion to variations in the thickness of the work.

12. A hook needle, chain stitch, inseam shoe sewing machine having, in combination, a needle and a channel guide located on one side of the work, said needle acting during its retracting stroke to exert a stitch tightening strain on the thread, a take-up acting to pull tight a loop of thread about the shank of the needle while the latter is in the work, 55 and a looper and thread finger upon the opposite side of the work and coacting to vary the point in the length of the thread extending from the channel to the looper at which the hook of the needle engages the thread prior to the needle's retraction, said variation being proportionate to the thickness of the work.

13. A hook needle, chain stitch, inseam shoe sewing machine having, in combination, a 60 needle and a channel guide located on one

side of the work, said needle acting during its retracting stroke to exert a stitch tightening strain on the thread, a take-up acting to pull tight a loop of thread about the shank of the needle while the latter is in the work and a looper and thread finger upon the opposite side of the work and coacting with the work to vary the length of the loop of thread given to the needle during its retracting stroke and after the needle hook enters the work in proportion to the thickness of the work.

In testimony whereof I have signed my name to this specification.

ANDREW EPPLER.
